CLAIM

The ornamental design for a pitcher, as shown and described.

DESCRIPTION

FIG. 1 is a perspective view of an embodiment of a pitcher showing the new design;

FIG. 2 is a right side elevation view of the pitcher of FIG. 1;

FIG. 3 is a left side elevation view of the pitcher shown in FIG. 1;

FIG. 4 is a front side elevation view of the pitcher shown in FIG. 1;

FIG. 5 is a rear elevation view of the pitcher shown in FIG. 1;

FIG. 6 is a top plan view of the pitcher shown in FIG. 1; and, FIG. 7 is a bottom plan view of the pitcher shown in FIG. 1.

The broken lines in the figures illustrate unclaimed environment and form no part of the claimed design.

1 Claim, 6 Drawing Sheets
